(57) **CLAIM**

The ornamental design for a encapsulated motion sensor illuminated toilet seat, as shown.

DESCRIPTION

FIG. 1 is a front right isometric view of a encapsulated motion sensor illuminated toilet seat showing my new design;
FIG. 2 is a back right isometric view thereof;
FIG. 3 is a top plan view thereof;
FIG. 4 is a right side plan view thereof;
FIG. 5 is a left side plan view thereof;
FIG. 6 is a front plan view thereof;
FIG. 7 is a back plan view thereof; and,
FIG. 8 is a bottom plan view.
